UNITED STATES PATENT OFFICE.

RICHARD VARLEY, OF ENGLEWOOD, NEW JERSEY.

ELECTRICAL SYSTEM.

1,225,535.

Specification of Letters Patent.

Patented May 8, 1917.

Original application filed April 27, 1915, Serial No. 24,252. Divided and this application filed September 29, 1915. Serial No. 53,196.

To all whom it may concern:

Be it known that I, RICHARD VARLEY, a citizen of the United States of America, residing at Englewood, in the county of Bergen and State of New Jersey, have invented 5 new and useful Improvements in Electrical Systems, of which the following is a specification.

This invention is an electrical system 10 wherein a high tension flow or discharge of current is effected at a current using instrumentality, such as a spark gap or the spark plug of a cylinder of an internal combustion engine; this case being a division of my 15 application for Letters Patent of the United States, filed April 27th, 1915, Serial No. 24,252.

As such a system I aim for high efficiency 20 in spark discharge or energizing of the current using instrument, simplicity of construction and arrangement and flexibility in control, in the provision of novel means comprising preferably a plurality of transformers, a source of current and means for bringing the transformers into and out of energizing circuit with the source of current and for controlling the operative discharges of said transformers, all as more fully set forth in the following description, which is 25 addressed to those skilled in the art and in which reference is made to the accompanying drawings, which show ignition systems embodying my invention.

While I have shown my invention as applied 30 to an ignition system whereby the gaseous charges in the cylinders of an internal combustion engine may be exploded, it will be understood that the invention is not limited in use, but, on account of the advantages obtained thereby, it finds desired embodiment in ignition systems. It will also be apparent that many changes may be made in the construction and arrangement shown without departing from my invention.

Figure 1 is a diagrammatic view of an 35 ignition system embodying my invention; Fig. 2 is a similar view, showing a manner of utilizing the magnetic flux of the transformer core to operate the current responsive interrupter mechanism associated with the respective transforming unit; Fig. 3 is a similar view showing a modified manner of mounting the interrupter mechanism and of disposing the windings on the legs of the 40 transformers; and Fig. 4 is a diagrammatic

view of a transformer unit showing modified manner of extending the legs of the transformer to constitute the magnetic core for the interrupter mechanism.

In Fig. 1 the numerals 2 indicate the cores 60 of transformers 3 that correspond generally with the transformer disclosed in Letters Patent No. 1,081,413, granted to me on December 16th, 1913; No. 1,103,385, granted to me July 24th, 1914, and No. 1,112,177, granted to me September 29th, 1914, in that each transformer is provided with a plurality of windings, herein indicated by the numerals 4 and 5, by means of which a magnetic flux is caused to be built up in the core to preferably a supernormal state for energizing of a 70 secondary winding 6, which is grounded and leads to a current using instrumentality, such as a spark plug (not shown) in the cylinder of an engine in the usual manner. Switch mechanism 7 is employed to establish between the windings 4 and an alternating current generator 8 or a source of continuous current, such as battery 9, circuit connections under control of roller timer mechanism 10 and interrupter or contact mechanism 11, in the manner hereinafter 75 more fully described.

The alternating current generator 8 (here 80 shown as of a type for a four-cylinder four-cycle engine) has its energizing circuit or inductive winding grounded at one end, as at 12, while the other end connects with switch contact 13, while the battery 9 is 85 grounded at 14 and leads to switch contact 15. Connected in the battery circuit is vibrator 16 across the contact of which may be connected the usual condenser 16a.

Controlling the circuit of the winding 5 90 of each transformer is contact mechanism or an interrupter comprising a fixed contact 17 and a movable contact 18, which latter contact is carried by an armature blade 19 arranged in attractive juxtaposition to a magnet core 20 the winding of which is in the circuit of the transformer winding 4, the connection preferably being in series, as shown. A condenser 21 may be connected across the contacts 17 and 18.

The roller timer mechanism 13 comprises 95 a contact arm 22 that is geared to be driven in synchronism with the engine, as in the usual manner, and a plurality of segments 23 which connect with the windings 4 of 100 the transformer. With the switch arm 7 110

shifted to contact 13 for magneto connection, it will be apparent that, with driving by the engine of the generator 8 to produce a suitable alternating current, travel of the timer arm 22 into engagement with a segment 23 will close the circuit of the respective transformer winding 4, through grounds 24 and 12; setting up a flux in the core of the transformer unit. The circuit 10 of the winding 5 is normally closed by the interrupter contacts 17 and 18, so that said winding acts as a choke upon the travel of the magnetic lines of force set up in the transformer core, causing a repression thereof from that particular portion of the core 15 in such manner that, with sufficient source strength, the lines of force tend to take a leakage path intermediate the sides or legs of the transformer. As the current wave 20 approaches or reaches its maximum point or period of flow, the core 20 of the interrupter mechanism 11 will be sufficiently energized, by reason of its winding being connected in the circuit of the winding 4, to attract the armature 19 and separate contact 25 18 from contact 17, thus suddenly opening the circuit of the choke coil or winding 5. Opening of the circuit of this winding 5 causes the repressed flux to assume the normal 30 magnetic path of the core, causing in the leg carrying the secondary winding 6, a magnetic surge of great intensity which immediately builds up in the secondary winding 6 a voltage capable of instantly breaking down or 35 bridging the gap of a spark plug or other device connected in circuit therewith. During the time when the roller timer arm 22 is in engagement with a segment 23, the winding 4 of the transformer remains in active 40 circuit with the generator so that during and after the first disruptive movement of the flux in the core, the tendency is to maintenance of an active state of flux for prolonged energizing of the current using instrumentality, all as clearly set forth in 45 my above mentioned Letters Patent No. 1,081,413.

By employing the roller timer 13 or other suitable contact mechanism for intermittently establishing the above mentioned circuit closure of the windings 4, I provide means for bringing the transformer windings 4 and the interrupter mechanisms 11 into circuit with the source of continuous current or the battery 9, when the magneto connection is broken and the switch arm 7 is shifted to contact 15. As a result of such switch connection the interrupter vibrator mechanism 16 is placed in active circuit 50 with the battery so that it vibratory responds to cause a pulsative flow of current from the battery through the transformer winding 4 when the roller timer arm 22 passes to a segment 23 and completes said 55 battery circuit through grounds 23 and 14.

Energizing of the winding 4, besides setting up a state of flux in the respective transformer, in the manner already described, causes energizing of the interrupter mechanism 11 for opening of the circuit of the winding 5 and energizing of the spark plug or other current using device in the circuit of the respective secondary winding 6 as is understood; the interrupter 11 of each transformer being preferably "lagged" 75 slightly behind the vibrator 16 so that the choke coil circuit or winding 5 of any transformer is opened before the battery circuit is opened by means of the interrupter or vibrator 16. 80

In Fig. 2 I show a system corresponding with that shown in Fig. 1 (and like parts of which accordingly bear like reference numerals) with the exception that the auxiliary vibrator or current responsive interrupter mechanisms 11 are here shown as having their electromagnets forming part of the transformers. This is preferably done by extending from the transformer core a leg portion 25 carrying an energizing winding 20^a in series with the winding 4. The arrangement is such that the flux of the transformer core assists the flux set up in the leg 25 by the winding 20^a so that very few ampere turns of the winding 20^a 95 are required. Furthermore, it provides a compact, self-contained arrangement. In this system shown in Fig. 2 it also will be noticed that the choke winding or controlling circuit 5 is disposed at opposite ends or 100 sides of the secondary winding 6. This brings the secondary winding into a more intimate and therefore influentially receptive inductive relationship to the core of the transformer and operates to reduce the 105 copper content or bulk of winding of both choke winding and secondary winding, resulting in compactness and saving in cost of production.

In lieu of extending the transformer core 110 in the manner shown in Fig. 2, to form a core 25 for the magnet of the interrupter mechanism, I may cause the rise and fall of the flux in the main core of the transformer unit to actuate the interrupter blade or armature. Such an arrangement is shown in 115 Fig. 3 the parts of which correspond to those of Fig. 2 and bear like reference numerals. In this system, the transformer core carries the armature blade 19^a in such manner that 120 it lies attractively adjacent the end of a leg carrying the active winding 4. It thus will be seen that control of the interrupter contacts 17 and 18 of the circuit of the winding 5 is effected solely through the transformer 125 *per se*, the extra winding 20^a shown in the preceding view, being eliminated. This direct action results in positiveness and dependence in operation besides having structural advantages in compactness of form 130

and simplicity of mounting of the interrupter blade or armature.

Of course, the core of the transformer may be extended to form a magnetic core 5 for the armature blade 19^a which core may still be energized without the employment of a supplemental winding. Such an arrangement is shown in Fig. 4 wherein the legs of the transformer core are extended at 10 2^a and 2^b in such manner as to form a substantially closed magnetic circuit for lines of force set up by the winding 4 of the transformer.

Having thus described my invention, what 15 I claim and desire to secure by Letters Patent is:

1. In electrical systems, a plurality of transformer units each of which is provided with a primary winding, a secondary winding inductively related thereto, and a circuit controlling said inductive relationship, a current responsive interrupter for said circuit, a source of energy, and means for intermittently successively connecting the primary windings in circuit with the source of energy.

2. In electrical systems, a plurality of transformer units, each of which is provided with a primary winding, a secondary winding inductively related thereto, a circuit controlling said inductive relationship, and a current responsive interrupter for said circuit, a source of energy and means for intermittently successively connecting the primary windings in circuit with the source of energy.

3. In electrical systems, a plurality of transformer units, each of which is provided with a primary winding, a secondary winding inductively related thereto, and a circuit controlling said inductive relationship, a current responsive interrupter for said circuit, a source of energy, and means for intermittently successively connecting the primary windings in circuit with the source of energy and the current responsive interrupter.

4. In electrical systems, a plurality of

transformer units, each of which is provided with a primary winding, a secondary winding inductively related thereto, a circuit controlling said inductive relationship, and a current responsive interrupter for said circuit, a source of energy, and means for intermittently successively connecting the primary windings and the current responsive interrupters in circuit with the source of energy.

5. In electrical systems, a plurality of transformer units each of which is provided with a primary winding, a secondary winding inductively related thereto, and a circuit controlling said inductive relationship, interrupter mechanism connected in the said controlling circuits, a source of alternating current, a source of continuous current, vibrator mechanism, and means for intermittently successively connecting the primary winding in circuit with the source of alternating current or in circuit with the source of continuous current and the vibrator mechanism.

6. In electrical systems, a plurality of transformer units each of which is adapted to charge a current using instrumentality, a plurality of choke coils controlling said transformers, a source of energy, and means for successively bringing said transformers into energizing circuit with the source of energy and for intermittently opening and closing the circuits of said choke coils.

7. In electrical systems, a plurality of transformer units adapted to charge a plurality of current using instrumentalities, a plurality of choke coils for controlling said transformers with respect to the current using instruments, a source of alternating current, a source of continuous current, means for successively connecting said transformers in energizing circuit with either said source, and means for successively opening the circuits of the choke coils.

In testimony whereof I have hereunto set my hand.

RICHARD VARLEY.
